CLAIM

The ornamental design for a shoe, as shown and described.

DESCRIPTION

FIG. 1 is a front perspective view of a shoe showing my new design;
FIG. 2 is a side view thereof;
FIG. 3 is a rear perspective view thereof;
FIG. 4 is a rear view thereof;

FIG. 5 is an opposite side rear perspective view thereof; and,
FIG. 6 is an opposite side view thereof.

The curved oblique shade lines represent a translucent or
transparent appearance. The broken lines depicting the
remainder of the shoe form no part of the claimed design.
